APPARATUS FOR CONDITIONING PACKAGES
OF YARN, ETC.

Vasser Woolley, Atlanta, Ga., assignor to Seydel-Woolley & Company, Atlanta, Ga., a copartnership of Georgia consisting of Paul Seydel, John R. Seydel, Vasser Woolley, Mildred Seydel and Bessie R. Woolley

Application March 16, 1944, Serial No. 526,747

4 Claims. (Cl. 68—205)

1

This invention relates to machines for conditioning yarn while in the form of packages such as bobbins, cones, spools or cops especially for setting the twist in the yarn. This application is in part a continuation of my Patent No. 2,347,978, dated May 2, 1944, in which the method or process per se is claimed.

It has been customary to apply the liquid to such yarn while the packages, which for convenience we will call bobbins, are travelling on a conveyor belt, or chain or through a revolving cylinder. A great difficulty in all of such machines has been the excessive wear on the moving parts which operate without lubrication under the spray of water and penetrant. In some cases steam is applied but this is injurious to the bobbins and a steam room takes up a great deal of space.

This invention is the result of extensive study of the conditions involved in this work. One object is to provide a satisfactory machine for uniformly applying the proper amount of liquid without spotting or damage to the yarn.

A special object is to provide a simple and inexpensive machine in which the packages require no moving devices to carry them through.

Another object is to provide a compact and inexpensive machine.

Accordingly the preferred form of machine embodies a casing having a vertical series of inclined baffles, grids or grilles arranged so that packages dropped on the upper baffle, roll or spin and fall down on to a lower grille and thence fall upon a lower grille and thence roll or spin out of the machine. Sprays of the desired liquid are blown or otherwise forced from opposite sides of the machine on to the moving packages between the grilles. Excess of liquid is thrown off by the impact upon the baffles and grilles. The used liquid passes through the grilles and back into the supply tank from which it is again forced from the spray heads to be used again until exhausted. This used liquid is preferably filtered before passing back into the supply tank.

The various grilles are preferably made readily removable to facilitate cleaning and also to permit substitution of different grilles. The excess liquid which flows through the upper grille is diverted from the treating chamber so as to prevent drops of liquid from falling upon the bobbins traveling over the lower grille and which would spot the yarn.

In order to control the amount of the penetrant solution to be applied to the yarn I regulate the pressure exerted upon the liquid or may

2

substitute spray heads of different sizes or adjust the discharge. I may also modify the action by substituting grilles of different design or different sizes of openings or partially closing the grilles.

Fig. 1 is a side view of a machine embodying one form of my invention parts being broken away and in section to show the interior with a number of bobbins tumbling through under treatment.

10 Fig. 2 is a front view of the same machine.

Fig. 3 is a vertical sectional view showing the upper work baffle and its collecting trough.

Fig. 4 is a vertical sectional view showing a part of the lower baffle and discharge port.

15 The upper part 5 of the casing constitutes the treating chamber with an inlet 6 for receiving the packages and an outlet 7 from which they are discharged. Leading inwardly from the inlet is an inclined shelf or baffle plate 8 which is preferably imperforate.

20 Projecting inwardly from the opposite side of the casing on a lower level is the upper inclined perforated grille 9. Below the introductory baffle and on a level below the upper grille is the lower inclined grille 10. These

25 grilles are so constructed and arranged that the bobbins or other packages of yarn fall by gravity and turn and tumble from the baffle to the upper grille, then to the lower grille and thence down the inclined discharge chute 11 which is inclined

30 at a less inclination than the grille 10 so as to slow up the packages as they are discharged. The grilles have suitable openings to allow liquid to pass but prevent the packages from getting caught or passing through. The chute is preferably made up of a number of smooth parallel rods spaced apart so as to leave ample space for liquid to pass through but prevent the packages from falling through.

35 The lower part 12 of the casing constitutes a reservoir for holding the treating liquid or penetrant. Beneath the baffle are located two spray heads 13 or nozzles preferably adjustable so as to control the spray which is discharged between the baffle 8 and the grille 9 to envelop the packages as they fall. Beneath the grille 9 are located two more spray heads 14 preferably adjustable and directed to envelop the packages as they fall from the upper grille to the lower grille and roll and tumble on to the discharge chute 11.

45 The penetrant liquid is drawn from the reservoir 12 and forced to the discharge spray heads by a circulating pump 15.

At the bottom of the treating chamber is a filter pad 16 for removing foreign particles from the treating liquid. An additional filter 17 is in-

3

terposed between the pump and the spray heads. In addition a pressure regulator 18 is interposed between the filter 17 and the spray heads.

To prevent liquid from dripping from the upper grille upon the packages beneath I provide a collecting trough or gutter 19 which discharges through a duct 20 which leads to a point beneath the chute 11 but above the filter pad 16.

Similarly a drip pan 21 is located beneath the lower grille 10.

Beneath this drip pan is an inlet opening 22 and a hinged baffle 23.

At the top of the casing is an electric lamp 24 for illuminating the treating chamber.

The opening 22 provides access to the interior for inspection and removal and insertion of parts and for filling the reservoir and for cleaning and flushing the tank, and the baffle 23 prevents escape of the penetrant liquid. The drip pan 21 deflects liquid from the lower grille beyond the baffle 23.

By using the spray heads in pairs I am able to get a much more uniform action in a relatively small space. Each head or nozzle produces a fine spray more like a mist than like a stream. The spray from these two heads intersects and fills the adjacent space so as to completely envelop the falling bobbins.

Proper conditioning of the yarn requires control of the solution applied to it. This is accomplished by adjustment of the regulating valve between the circulating pump and the spray heads, by using proper capacity of heads, adjustment of the orifice of each spray head so as to produce the desired enveloping mist and by modifying or properly designing the contact areas of the inclined grilles or grids. As the bobbins roll down these grids they come in contact with the surfaces which are wet from the spray and thus pick up moisture by contact. In fact in some cases part of the baffles or grids may be covered with imperforate plates so that more liquid may be picked up.

Another important feature is the removal of excessive moisture which might fall in large drops like rain from the lower edge of the upper grille to the bobbins as they pass down the lower grille. This would cause the yarn to become spotted or excessively wet in spots. This trouble has been overcome by the use of a gutter to lead the excess moisture out of the path of the falling bobbins.

The grids may be satisfactorily formed of hard, non-corrosive metal such as Monel metal or stainless steel held properly in place and preferably readily removable. The solid covers for the grids may be formed of Micarta or non-corrosive metal not affected by the penetrant liquid.

The apparatus herein set forth is very simple in construction and durable. The original cost is very much less than any known prior art yarn conditioning machine. In fact the cost of replacement and repair is only a small fraction of the cost of upkeep of machines which employ moving aprons or drums, and the result of the process is a better conditioned package.

One great advantage of the present apparatus is that the yarn is better and more uniformly conditioned because of the rolling, turning motion as the bobbins descend the inclined grids and baffles and retain their spinning motion while falling through space. The entire circumference of each package is thus exposed to the fine spray and uniform wetting takes place. The operation also takes place at a higher speed as the bobbins pass quickly through the treating chamber. There is

4

no way for the bobbins to get caught. The wooden bobbins or spools do not have a chance to become soaked either on the outside or inside which soaking would tend to cause the bobbins to swell and crack and deteriorate.

I claim:

1. Apparatus for conditioning packages such as bobbins, cops and the like filled with yarn comprising a vertically disposed treating chamber having a number of stationary successively oppositely inclined grilles vertically disposed one above the other and in staggered arrangement and inclined downwardly toward the center of the chamber, an inclined introductory baffle in the upper part of said treating chamber above said grilles and a stationary inclined discharge chute below said grilles, said baffle, grilles and chute being arranged so that bobbins introduced at the top of said chamber will fall by gravity from the baffle, then to one grille, then to the next grille and then pass down said chute without the application of any moving parts, a reservoir containing the treating liquid arranged below said treating chamber and means for withdrawing liquid from said reservoir and discharging it into said treating chamber from opposite sides thereof so as to substantially fill the space beneath said introductory baffle and above said discharge chute with a fine mist enveloping the packages as they fall from the baffle to the chute.

2. Apparatus for conditioning packages of yarn comprising a vertically disposed casing having an upper treating chamber, a lower liquid reservoir, an introductory baffle in the upper part of said chamber, upper and lower stationary successively oppositely inclined grilles vertically spaced from each other on opposite sides of the treating chamber below said baffle, said upper grille being inclined oppositely of said baffle and said grilles being inclined downwardly toward the center of the casing, spray heads on opposite sides of the casing for delivering a fine mist of conditioning liquid upon the packages as they fall from the baffle on to the upper grille and from the upper grille to the lower grille, a circulating pump for drawing liquid from the reservoir and forcing it from the spray heads and a discharge chute below said lower grille whereby packages inserted into the upper part of said chamber will pass automatically through said chamber and be discharged therefrom by gravity.

3. Apparatus for conditioning packages of yarn comprising a vertically disposed casing having an upper treating chamber, a lower liquid reservoir, a filter member between the chamber and reservoir, an introductory baffle, upper and lower stationary oppositely inclined grilles on opposite sides of the treating chamber, said upper inclined grille being inclined oppositely to said introductory baffle, and said grilles being relatively staggered and downwardly inclined toward the center of said casing, spray heads on opposite sides of the casing for delivering a fine mist of liquid upon the packages as they fall from the baffle on to the upper grille and from the upper grille to the lower grille, a circulating pump for drawing liquid from the reservoir and forcing it from the spray heads and a filter interposed between the pump and the spray heads.

4. A machine for conditioning yarn in packages comprising a casing having a liquid containing reservoir with a vertically disposed treating chamber above it, a filtering pad located between said reservoir and said chamber, an introductory baffle in the upper part of the treating chamber

inclined downwardly toward the center of the chamber at one side thereof, an upper grille in the opposite side of said chamber inclined downwardly toward the center of the chamber, a collecting gutter immediately beneath said grille having a duct for returning the liquid collected by said gutter to the chamber above said filter pad, a lower grille in said chamber on the same side of the chamber as the introductory baffle at a level below the upper grille and beneath the introductory baffle inclined downwardly in the same direction as the introductory baffle toward

the center of the chamber, an inclined discharge chute leading from said lower grille, a spray nozzle leading into said chamber on one side thereof beneath said baffle for spraying liquid upon packages falling from said baffle upon the upper grille, a second spray nozzle leading into said chamber on the opposite side thereof between said grilles for spraying liquid upon packages falling from the upper grille upon the lower grille and a pump for withdrawing liquid from said reservoir and forcing it through said spray nozzles.

VASSER WCOLLEY.
